CASH REGISTER

Richard Fellenberg, Berlin, Germany, assignor
to The National Cash Register Company, Dayton, Ohio, a corporation of Maryland

Application May 16, 1934, Serial No. 725,995
In Germany May 29, 1933

18 Claims. (Cl. 235—130)

This invention relates to improvements in cash registers of the type illustrated and described in Letters Patent of the U. S. No. 751,611 issued February 9, 1904 to Thomas Carroll and Patent No. 1,594,167 issued July 27, 1926 to Frederick L. Fuller.

Broadly, it is an object of this invention to incorporate in machines of the type referred to in the above patents mechanism to print totals directly from the totalizer wheels.

In such registers, where the totals are printed directly from the totalizer wheels, and the totalizer reset by means of an insertable key or wrench, it is necessary to incorporate mechanism in the machine to enforce proper operation of the total printing and resetting mechanisms. In order to safeguard against fraud or mal-operation of the total printing and resetting mechanism, it is necessary to permit access to such mechanisms only to those in authority. Therefore, it is, also an object of this invention to provide means to enforce correct operation of the totalizer resetting mechanism and the total printing mechanism.

Another object is to provide mechanism to prevent operation of the machine and to give access to the total printing means in sub-total taking operations.

Another object is to supply locking means to prevent operation of the machine, give access to the total printing means and the totalizer resetting means in total taking operations.

Still another object is the provision of means to render the total and sub-total printing means inoperative after one impression has been made.

A further object is to furnish means to prevent more than one operation of the total and sub-total printing means for each operation of the sub-total locking means.

Another object is to supply means to prevent more than one operation of the total printing means for each operation of the totalizer resetting mechanism.

Another object is to provide means to prevent removal of the reset wrench once it is properly inserted in the machine until the total printing lever has been given an initial movement and the wrench has been fully operated to perform a complete resetting operation.

Another object is the provision of means to stop the totalizer resetting mechanism after one resetting movement thereof, said stopping means also adapted to actuate mechanism that enforces machine operation between resettings of the totalizer.

A further object is to supply means to shift

the inking ribbon when the totalizer reset wrench is inserted in the machine in order that totals may be printed in a distinctive color.

A still further object is to provide means to prevent operation of the total and sub-total printing means when a slip of record material is not inserted therein.

With these and incidental objects in view the invention includes certain novel features of construction and combination of parts, the essential elements of which are set forth in appended claims and a preferred form or embodiment of which is hereinafter described with reference to the drawings which accompany and form a part of this specification.

Of said drawings:

Fig. 1 is a side elevation of the machine, depicting the locking mechanism for controlling the totalizer resetting and total and sub-total printing mechanisms.

Fig. 2 is a side view of the mechanism that controls the manipulation of the total printing lever and the resetting wrench.

Fig. 3 portrays the mechanism that controls the X and Z printing segment and the resetting special counter.

Fig. 4 is a side view of a part of the mechanism illustrated in Fig. 3, showing the positions these parts occupy when the reset wrench is inserted in the machine.

Fig. 5 is a front fragmentary view of the reset counter and the mechanisms shown in Figs. 3 and 4.

Fig. 6 is a detail view of the reset wrench.

Fig. 7 is a side view illustrating the mechanism for selecting and operating the transaction special counters.

Fig. 8 is a detail view of a part of the mechanism shown in Fig. 7.

Fig. 9 is a detail view as observed from the left of the machine, depicting in particular the full-stroke device for the total printing mechanism.

Fig. 10 is a front view of the transaction special counters and their operating mechanism.

Fig. 11 is a fragmentary view as observed from the rear of the machine, illustrating the total impression hammer and the ribbon carrying frame.

Fig. 12 is a right side view of the impression mechanism and portrays in particular the mechanism for shifting the ribbon when the totalizer reset wrench is inserted in the machine.

Fig. 13 is a detail view of the transaction counters zeroizing mechanism.

Fig. 14 is a sectional view of the impression hammer, and depicts the slip feeler mechanism that locks the total printing lever against manipulation until a record slip is inserted in the 5 aperture provided therefor.

General description

In the instant machine the total is printed directly from the wheels of the totalizer, which 10 serve both as accumulator wheels and as type carriers. The printing mechanism including the lever for operating the printing hammer, is accessible through a closure which is normally locked, and this locking means is controlled by a 15 sub-total lock and a total and reset lock, the keys of which are in the possession of some authorized person. The accumulator is reset by means of an insertable wrench and the aperture for the wrench is normally obstructed by a shutter, 20 which is controlled by the total and reset lock.

When it is desired to take a reading or sub-total of the accumulator the sub-total lock is manipulated by means of the key, and this locks the machine against operation and simultaneously 25 unlocks the closure and the total printing lever. A slip of record material may then be inserted in the printer and manipulation of the printing lever causes the sub-total to be printed.

A feeler mechanism prevents the manipulation 30 of the printing lever until a record slip is properly inserted in the machine. After the impression is taken the printing lever is locked in moved position until the sub-total lock is turned back to locking position. This releases the printing lever, which is then spring-returned to normal 35 position. A full-stroke device enforces complete movement of the printing lever in either direction. Each time the sub-total lock is unlocked, a step-by-step counter is advanced one unit to 40 count the number of sub-totalizing operations.

Unlocking the total and reset lock unlocks the closure giving access to the printing mechanism. In addition the total and reset lock removes the 45 obstruction from the totalizer reset aperture, renders the special transaction counters visible by removing the flash therefrom, and uncovers the reset aperture for said special transaction counters.

Inserting the reset wrench in the totalizer 50 aperture sets the X and Z printing segment, unlocks the printing lever, causes one to be added on a step-by-step printing counter, and actuates mechanism that locks the reset wrench in the aperture until it has been turned one revolution 55 to reset the wheels of the totalizer. However, the reset wrench is locked against rotation until the total printing lever receives initial printing movement, in order to enforce recording of the total before the totalizer wheels are reset to 60 zero.

As in sub-totalizing operations, the total printing lever is locked in moved position and is not released until the reset wrench is removed from the machine. Removing the reset wrench from 65 the aperture unlocks the total printing lever, which is then spring-returned to normal position. The act of inserting the total reset wrench in the aperture shifts a bi-chrome inking ribbon for the total printing device to a position where 70 the total will be printed in a distinctive color. It is obvious that the only time it is possible to reset the special transaction counters is when the total and reset lock is unlocked.

The mechanism outlined in a general way 75 above will now be described in detail.

Detailed description

The mechanism of this invention may be incorporated in most any type of cash register where the total is printed directly from the totalizer wheels, and inasmuch as the instant invention relates particularly to locking mechanism to control the functions of the total printing and resetting mechanisms it is felt that a description of only the register mechanisms affected by the mechanisms of this invention will 10 be sufficient.

Sub-total control mechanism

Directing attention to Figs. 1 and 5, the mechanism is enclosed in a suitable cabinet 29 secured to a machine base (not shown). Secured on a right machine frame 30 is a sub-total lock 31, the barrel of which carries a stud 32, which extends within a slot in an upwardly disposed extension of a lever 33 pivoted on a stud 34 secured in the right frame. A downward extension of the lever 33 has a foot 35 which cooperates with a stud 36 in a rearwardly disposed arm of a main shaft locking pawl 37 loose on a stud 38 secured in the right frame. A downward extension 39 of the pawl 37 cooperates with an abrupt surface 40 of a disk 41 secured on a main drive shaft 42 journaled in the main frames of the machine. A spring 43 urges the pawl 37 clockwise to normally maintain a right angled projection 44 thereof in contact with the edge of a lever 45 rotatably supported by the stud 38. The lever 33 has an extension 46 which cooperates with an arm 47 of a step-by-step counter 48. A forwardly disposed arm 49 of the lever 33 cooperates with a stud 50 in a slide 51 supported by two parallel slots in cooperation with a pair of studs 52 secured in the machine frame. A projection 53 of the slide 51 normally engages an extension 54 of a closure locking bar 55 slidably mounted on the inside surface of the cabinet 29 and urged upwardly by a spring 56 so that its upward end normally engages a hook 57 secured to a closure 58 hinged to the machine cabinet 29. A spring 59 is tensioned to urge the slide 51 upwardly, causing the stud 50 to be held in contact with a lower surface of the arm 49 of the lever 33.

Unlocking the sub-total lock 31 revolves the barrel thereof in a clockwise direction, which by means of the stud 32 rocks the lever 33 counter clockwise causing the foot 35 in cooperation with the stud 36 to rock the pawl 37 counter clockwise to move the projection 39 in the path of the step 49 to prevent clockwise movement of the main drive shaft 42. This movement of the lever 33 by means of the extension 46 in cooperation with the arm 47 causes one to be added on the step-by-step counter 48. Counter clockwise movement of the lever 33 by means of the arm 49 thereof, in cooperation with the stud 50 moves the slide 51 downwardly, which movement, by means of the projection 53 is obviously transmitted to the locking bar 55 to disengage said bar from the hook 57 of the closure 58. After the closure has thus been unlocked a spring (not shown) opens the closure sufficiently to permit a finger-hold thereon, so that it may be opened the remainder of the distance by hand.

The upwardly disposed arm of the lever 33 carries a stud 60 which extends through a slot in the rearward end of a link 61, the forward end of which is pivoted to a lever 62 (Figs. 1 and 2) fulcrumed on a fixed stud 63. A hook-shaped 75

downward extension of the lever 62 terminates in a rounded nose 64 which cooperates with the edge of lever 65 loose on a stud 66. The lower portion of the lever 65 (Fig. 2) has a right angled 5 extension 67 which cooperates with a lug 68 on a total printing lever 69 secured to a shaft 70 journaled in uprights of a front frame 71. A torsion spring 72 urges the lever 69 clockwise to normally maintain the lug 68 in contact with an 10 upward extension of the frame 71. A spring 73 tensioned between the levers 62 and 65 urges said levers clockwise to normally maintain the extension 67 of the lever 65 in the path of the lug 68 and to retain the lever 62 in its normal 15 position. The upper portion of the lever 65 has a nose 74 which cooperates with a bent-over ear 75 of a locking arm 76 loose on the stud 66 and flexibly connected by a spring 77 to the lever 65, said spring normally maintaining the nose 74 in 20 contact with the ear 75. The arm 76 has a forward extension 78 which cooperates with a stud 79 in the total printing lever 69.

Referring to Figs. 1 and 2, unlocking the sub-total lock 31, as previously stated, rocks the lever 25 33 counter clockwise which movement by means of the link 61 is transmitted to the lever 62. Counter clockwise movement of the lever 62 causes the nose 64 thereof to engage and rock the lever 65 also in a counter clockwise direction 30 to move the projection 67 out of the path of the lug 68 of the total printing lever 69. The spring 77 tends to move the arm 76 counter clockwise in unison with the lever 65, however, the stud 79 in cooperation with an angular surface of the 35 extension 78 prevents such movement of the arm 76. Consequently the spring 77 receives added tension by counter clockwise movement of the lever 65. From the foregoing it will be seen that the spring 73 (Fig. 2) normally holds the 40 projection 67 of the lever 65 in the path of the lug 68 to block counter clockwise printing movement of the total printing lever 69 until the sub-total lock 31 (Fig. 1) is unlocked.

Directing attention to Figs. 11 and 12, secured 45 on the shaft 79 are symmetrical eccentrics 83 and 84 straddled by the bifurcated lower ends of plates 85 and 86 loose on studs 87 secured in the side members of a printer platen frame 88 loose on a shaft 89 supported by the uprights of the 50 front frame 71. Adjustably mounted on the side members of the platen frame 88 are identical eccentrics 80, which in cooperation with the upper bifurcated ends of the plates 85 and 86 provide a means of adjusting the platen frame 89 55 and a platen block 91 in relation to a series of totalizer wheels 92. The printing totalizer wheels 92 are loose on a shaft 93 supported by a totalizer frame 94 (Figs. 5 and 12) which is adapted to move downwardly in the well known manner 60 to engage the totalizer with the actuators, and after the wheels of said totalizer have been actuated the totalizer frame is returned upwardly to normal printing position, as here shown.

A slip feeler mechanism locks the total printing lever 69 (Figs. 2 and 14) against manipulation until a slip of record material is inserted in the printing mechanism. When a record slip 95 is inserted in an aperture 96 in the platen frame 88 it engages an upward extension of a feeler 70 97 and rocks said feeler clockwise on its pivot on a bracket 98 secured to the platen frame 88. This clockwise movement of the feeler 97 disengages a hook 99 thereof from a step cut in a hub 100 secured on the shaft 79 (see also Fig. 11). 75 A shield 101 secured to the platen frame guides

the slip 95 between the platen block 91 and an inking ribbon 102. The shield 101 also holds the inking ribbon 102 away from the platen block 91 and the record strip to prevent blurring said record strip when it is inserted in the machine. 5 It will be seen by observing Fig. 11 that the platen block 91 has raised portions corresponding to the lateral spacing of the totalizer wheels. These raised portions register with openings in the shield 101 through which the platen 91 forces 10 the inking ribbon 102 and the record strip 95 into contact with the totalizer wheels 92 to make an impression on said slip.

Unlocking the sub-total lock (Figs. 2, 12, and 14) frees the total printing lever 69, as explained 15 above, for counter clockwise movement (Figs. 2, 12, and 14) to print a reading or a sub-total of the amount on the wheels of the totalizers. Moving the lever 69 counter clockwise rocks the shaft 70 also counter clockwise, which by means 20 of the eccentrics 83 and 84 imparts a clockwise movement to the platen frame 88. This causes the platen 91 to press the inking ribbon 102 and the record slip 95 against the totalizer wheels 92 to print the amount thereon. 25

Counter clockwise movement of the total printing lever 69 (Fig. 2) moves the stud 79 beyond the extension 78. The spring 77 is then free to urge the arm 76 counter clockwise to move the arcuate portion of said extension 78 into the 30 path of the stud 79 to block return movement of the printing lever 69. The lever 69 remains thus locked inoperative until the sub-total lock 31 is locked, which movement returns the lever 33 clockwise to the position here shown and allows 35 the spring 43 to move the extension 39 of the pawl 37 out of the path of the abrupt surface 40 to free the machine for operation. Clockwise return movement of the lever 33 allows the spring 73 (Fig. 2) to return the levers 62 and 65 also in a 40 clockwise direction. The nose 74 of said lever 65 in cooperation with the ear 75 returns the arm 76 in unison therewith. There is enough clearance between the periphery of the lug 68 and the extension 67 to allow the arm 76 to move sufficiently 45 clockwise to cause the arcuate surface of the extension 78 to move slightly beyond the stud 79. The spring 72 is then free to return the total printing lever 69 to normal position, the stud 79 cooperating with the angular surface of the extension 78, restores the arm 76 to home position, and the springs 73 and 77 return the lever 65 50 so that the projection 67 is in the path of the lug 68 to again block printing movement of the lever 69. 55

Locking the sub-total lock 31 and consequent return movement clockwise of the lever 33 allows the spring 59 to return the closure locking slide 54 upwardly, which in turn allows the spring 56 to return the locking bar 55 upwardly so that the upper end thereof is in the path of the closure latch 57. Shutting the closure 58 causes the hook 57 to latch over the upper end of the bar 55 to lock the closure 58.

From the foregoing description it can be seen 65 that for each operation of the sub-total lock 31 (Fig. 1) the total printing lever 69 can be operated through only one complete cycle of movement. It is, therefore, obvious that the number of sub-totals printed can never be greater than 70 the number on the step by step counter 48 and if the total printing lever has been operated each time the subtotal lock 31 has been unlocked the number of subtotals printed will agree with the number on the step-by-step counter 48, which it 75

will be recalled, counts the number of times the sub-total lock 31 is operated.

Total printing full-stroke device

5 Fig. 9 clearly illustrates a device for enforcing full stroke of the total printing lever 69. This mechanism consists of a full-stroke ratchet segment 103 secured on the shaft 70 and having teeth which cooperate with the lower end of a full-
10 stroke pawl 104 pivoted at 105 to a stationary plate 107 supported by the shafts 70 and 80. A spring 107 tensioned between the pawl 104 and the plate 106 holds said pawl in position to ratchet over the teeth in the segment 103 regardless of
15 the direction in which the segment is moving. Moving the total printing lever 69 clockwise, as viewed in Fig. 9, to make an impression, causes the teeth of the segment 103 to engage the ratchet pawl to prevent the lever 69 from being backed up or returned until its full stroke is completed.
20 In a like manner, a full return stroke of the lever 69 is enforced.

Total printing and total reset control lock mechanism

25 The printing of the total and the resetting of the totalizer to zero is under the control of a total lock 108 (Fig. 1), similar to the sub-total lock 31. The barrel of the total lock 108 carries a stud 109 which extends through a slot in the upward arm of a lever 110 pivoted at 111 to the right machine frame. The lower end of the lever 110 carries a stud 112 which extends through a slot in the lever 45. Normally the upper portion 30 of the lever 45 covers an aperture 113 for the reception of a totalizer reset wrench 114 (Fig. 6).
35

A forward extension of the lever 45 has a flat surface 115 (Fig. 1) which cooperates with the stud 50 in the slide 51. A link 116 pivotally connects the lever 45 to a shutter 117 adapted to normally cover an aperture 118 for the reset wrench 114 (Fig. 6), which is used to reset the wheels of an operation counter 119 (Fig. 10) and a plurality of transaction counters 120, the wheels 45 of which are rotatably supported by a shaft 121 journaled in special counter frames 122 and 123. The shutter 117 (Fig. 1) carries a stud 124 which cooperates with a slot in an arm 125 loose on the shaft 121 and supporting the righthand end of a flash 126, the lefthand end of which is supported by an arm similar to the arm 125 which is also loose on the reset shaft 121. Normally the flash 126 covers an opening 127 in the cabinet 29 through which the wheels of the special counters 55 are visible.

Inserting the key and turning the barrel of the lock 108 (Fig. 1) in a counter clockwise direction, by means of the stud 109, rocks the lever 110 clockwise, which by means of the stud 112 implants 60 counter clockwise movement to the lever 45. Counter clockwise movement of the lever 45 uncovers the aperture 113 for the reset wrench and causes the surface 115 to engage the stud 50 to move the slide 51 downwardly to unlock the closure 58 in exactly the same manner as explained for the sub-total lock mechanism. This initial counter clockwise movement of the lever 45 by means of the link 116, pivotally connected to arm 81 riveted to lever 45 at 82, rocks the shutter 117 65 clockwise to the positions shown in dot and dash lines to uncover the reset aperture for the special counter. Clockwise movement of the shutter 117 by means of the stud 124 and the arm 125 rotates the flash 126 counter clockwise to uncover the 70 opening 127 so that the wheels of the special 75

counters are visible therethrough. Counter clockwise unlocking movement of the lever 45 by means of the projection 44 moves the pawl 37 in unison therewith to place the projection 39 thereof in the path of the step 40 to frustrate attempts to operate the machine during total printing and resetting operations.

Each of the totalizer wheels 92 (Fig. 5) has secured thereto a gear 128 connected by an intermediate gear 129, loose on a shaft 133 supported by the totalizer frame 94, to an actuating gear 134 loose on a reset shaft 135 supported by the totalizer frame 94. Each of the gears 134 carries a pawl adapted to be engaged by a lateral groove in the reset shaft 135 to revolve said gears in unison therewith when the shaft is turned counter clockwise, as viewed in Fig. 3 by means of the reset wrench 114 (Figs. 4 and 6). Counter clockwise resetting movement of the gears 134 by means of the gears 128 and 129 is transmitted to the totalizer wheels 92 in order to reset said wheels to zero position. Secured on the righthand end of the reset shaft 135 is a partial disk 136 the hub of which has a clutch cut 137 adapted to receive tenons 138 (Figs. 3 and 6) of the reset wrench 25 114.

Calling attention to Fig. 3, the upper portion of the clutch cut 137 is normally engaged by a bent-over tongue 139 of an arm 140 loose on a stud 141 secured in the totalizer frame 94. The forward end of the arm 140 is pivotally connected by a link 132 to a symbol printing segment 142 loose on the totalizer shaft 93. The rearwardly disposed portion of the arm 140 has a right angled extension 143 which cooperates with the rounded lower end of a pitman 144 slotted to receive a stationary stud 145. The upper end of the pitman 144 is pivoted to an arm 146 fast on a tube 147 loose on a shaft 148 opposite ends of which are supported by upward extensions of the side 40 frame 30 and a cross frame 149. Pivoted to a downward extension of the arm 140 is a retaining plate 150 having two notches which are urged by a spring 153 into communication with the pointed end of an extension 151 of an arm 152 loose on the stud 141.

The aperture 113 (Figs. 3 and 4) for the reset wrench is notched to receive lugs 154 and 155 on said wrench thereby insuring proper insertion of said wrench in the aperture. It will be noted that 50 the arm 140 is spring urged clockwise to normally hold the tongue 139 in the clutch cut 137 to retain the reset shaft 135 in home position when the reset wrench is removed. The righthand end of the reset shaft 135 (Fig. 5) terminates in a 55 pointed tenon, which in cooperation with a hole in the end of the reset wrench 114 (Fig. 6) guides and supports said wrench during resetting operations.

Inserting the wrench 114 in the aperture 113 60 causes the beveled edge of the upper tenon 138 as viewed in Fig. 6 to engage and force the tongue 139 (Fig. 3) out of the clutch cut 137 and rock the arm 140 counter clockwise. Counter clockwise movement of the arm 140 rocks an edge 156 of the 65 arm 152 into cut-away portion 157 of the wrench 114 (see also Figs. 4 and 6) to prevent removing the wrench until the resetting operation is completed. This counter clockwise movement of the arm 140 by means of the link 132 rocks the segment 142 counter clockwise so that the symbol "Z" for a total printing operation is aligned with the printing mechanism.

Counter clockwise movement of the arm 140, by means of the extension 143, raises the pitman 70 75

144 to rock the arm 146 and the tube 147 clockwise to cause an arm 158 carried by said tube, in cooperation with a yoke 159 (Fig. 5) to add one on the printing wheels of a step by step counter 5 160 which indicates the number of times the totalizer has been reset. The counter 160 does not move up and down with the totalizer frame 94 but is fixedly supported by a bracket on the cross-frame 149.

10 *Ribbon shifting mechanism*

Secured on the tube 147 (Fig. 12) is a pair of arms 161 connected by links 162 to symmetrical arms 163 pivoted to a stationary cross-frame of 15 the machine. The forward ends of the arms 163 extend within openings 164 (Fig. 11) of a ribbon support plate 165 slidably mounted in the platen frame 88. Upwardly extending arms of the plate 165 are notched to support the bi-chrome ribbon 20 102 in proper relation to the platen block 91 (see also Fig. 14). Normally the upper edge of the ribbon 102 (Figs. 12 and 14) is opposite the printing position. However, inserting the reset key in the machine rocks the tube 147 clockwise against 25 the tension of a spring 166 which by means of the arms 161, links 162 and arms 163, shifts the ribbon support plate 165 upwardly to move the lower portion of the ribbon 102 into printing position so that totals and sub-totals will be printed in 30 distinguishable colors.

35 Directing attention to Fig. 2, upward movement of the pitman 144 by means of a stud 167 therein, imparts counter clockwise movement to the lever 62, which movement is transmitted to the lever 65 to move the extension 67 out of the path of the lug 68 on the total printing lever 69. An extension 168 of the arm 76 in cooperation 40 with the lug 154 blocks resetting movement of the reset wrench 114 until after a total has been printed. This is to enforce a recording of the total before the wheels of the totalizer are turned to zero. Moving the total printing lever 69 (Fig. 2) counter clockwise, in order to print a total, moves the stud 79 beyond the extension 45 78 of the arm 76, allowing the spring 71 to rotate said arm counter clockwise until the ear 75 engages the nose 74 of the lever 65. The arcuate surface of the extension 78 drops behind the stud 79 and prevents return or clockwise movement 50 of the lever 69 and the projection 168 moves out of the path of the lug 154 so that it is now possible to turn the reset wrench 114 in a counter clockwise direction to reset the wheels of the totalizer. Reverse or clockwise movement of the 55 reset shaft 135 is prevented by means of a ratchet and pawl (not shown).

As the reset wrench 114 (Figs. 2, 5, and 6) is turned counter clockwise, the lugs 154 and 155 move beyond the opening in the aperture and 60 straddle the side wall of the machine frame 30 to further prevent said reset wrench being withdrawn before a complete resetting movement is made. The lug 154 (Figs. 3 and 4) engages the surface 156 of the arm 152 and rocks said arm 65 clockwise on its pivot 141, causing the pointed end thereof to move from the lower notch to the upper notch in the plate 150. This position of the arm 152 is indicated by dot and dash lines in Fig. 4. Continued rotation of the reset wrench through 70 one counter clockwise revolution resets the wheels of the totalizer to zero.

In order to prevent duplicate or repeat operations of the reset wrench, mechanism is provided to block movement of said wrench after one revolution thereof. This mechanism remains effec- 75

tive until a regular operation of the machine is performed, thereby enforcing removal of the reset wrench and operation of the machine before the wheels of the totalizer can be again turned to zero. Near the end of the resetting revolution 5 of the reset shaft 135 (Fig. 3) a stud 169 carried by the disk 136 engages a projection 170 of an arm 171 loose on the stud 145. This rotates the arm 171 clockwise until another projection 173 thereof engages a fixed stud 174. This prevents 10 further movement of the reset wrench 114 and alines the reset shaft 135 in home position so that the reset wrench may now be removed.

Pivoted on the arm 171 is a shutter 175 having a projection which is urged clockwise into contact with a stud 176 in said arm 171 by a spring 177 which flexibly connects the shutter 175 and the arm 171. Clockwise movement of the arm 171, as explained above, causes the rounded lower end of the shutter 175 to engage the shank of 20 the reset wrench 114 (Fig. 6) which obstructs further unitary movement of the shutter 175 and the arm 171 and said arm 171 continuous to move relatively to the shutter, flexing the spring 177. When the reset wrench is removed from 25 its aperture the spring 177 rocks the shutter 175 clockwise so that the rounded lower end thereof moves into the aperture for the reset wrench to obstruct or prevent insertion of said reset wrench therein until after a machine operation has been 30 performed.

Subsequent operation of the machine causes the totalizer frame 94 (Figs. 3 and 5) to move downwardly to engage the gears 134 with the differential actuators. This moves the stud 169 35 downwardly out of the path of the projection 170, allowing the spring 172 to return the arm 171 counter clockwise to normal position, as shown in Fig. 3, which position is determined by a stop stud 178 in the frame 30 cooperating with said 40 arm 171. This return movement of the arm 171 carries the shutter 175 to the position shown in Fig. 3, so that it no longer obstructs the aperture for the reset wrench. Return movement upwardly of the totalizer frame 94 causes the stud 169 to move in front of the projection 170 of the 45 arm 171. This further prevents a reverse movement of the reset shaft 135 when the reset wrench is inserted in the machine.

55 Removing the reset wrench 114 (Figs. 2, 3, and 4) allows a spring 179 to return the arm 140 and the symbol printing segment 142 clockwise to normal position so that the lug 139 again engages the clutch cut in the hub of the disk 136 and the segment 142 is in position to print the symbol "X" for a sub-total taking operation. This return movement of the arm 140 allows the pitman 144 and the tube 147 to be returned counter clockwise under the influence of the spring 166 to move the stud 167 (Fig. 2) away from the lever 62, thereby allowing said lever to be returned clockwise to normal position by the spring 73. The spring 73 also returns the lever 65 clockwise to move the arcuate surface of the extension 78 of the arm 76 beyond the stud 79 to allow the 60 total printing lever 69 to be returned to home position by the torsion spring 72 in exactly the same manner as described for sub-total printing operations.

65 Return movement clockwise of the arm 140 caused by removing the reset wrench causes an extension 180 (Figs. 3 and 4) of the arm 152 to engage the periphery of the hub of the disk 136 to shift said arm counter clockwise from the position shown in dot and dash lines in Fig. 4 to 75

its normal position as shown by full lines in Figs. 3 and 4.

It will be recalled by observing Fig. 1 that after the printing of a sub-total, the sub-total lock 31 may be turned counter clockwise to locked position to condition the machine for operation by removing the projection 39 of the pawl 37 out of the path of the disk 41. Also, that after a total is printed, the totalizer reset to zero, and the reset wrench removed from the machine the total lock 108 may be rotated counter clockwise back to locking position as here shown. This also moves the pawl 37 to ineffective position. As an added precaution means have been provided for retaining the machine locked against operation unless the total printing lever 69 (Fig. 2) is fully returned clockwise to normal position by the spring 72. This mechanism includes a stud 183 (Figs. 1 and 2) secured in the total printing lever 69 which cooperates with the forward end of a lever 184 pivoted at 185 to the machine frame 30. Moving the lever 69 counter clockwise to print a total causes the stud 183 to rock the lever 184 counter clockwise to cause a right angled projection 186 thereof in cooperation with the projection 39 to retain the pawl 37 in effective position until the total printing lever 69 is returned clockwise fully to home position.

The pawl 37 is also under control of a lock 187, the barrel of which carries a pin 188 which cooperates with an undercut portion of the rearward extension of said pawl 37. Turning the barrel of the lock 187 clockwise to locking position causes the stud 188 to rock the pawl 37 counter clockwise to move the projection 39 thereof into the path of the step 40 of the locking disk 41 to lock the machine against operation.

40 Special transaction counter mechanism

It will be recalled by referring to Fig. 1 that unlocking the total control lock 108 rocks the shutter 117 and the flash 126 to the positions indicated by dot and dash lines to unobstruct the aperture for the turn-to-zero wrench and to uncover the wheels of the special counters. A torsion spring 189 cooperating with the shutter 117 returns said shutter and connected parts to normal position when the total control lock is turned to locking position.

In case it is desirable to have the wheels of the special counters visible in both total and sub-total printing operations, and allow the shutter 117 to remain under control of the total lock, it is necessary only to disconnect the flash arm 125 from the shutter 117 by removing the stud 124 and provide a similar arm minus the rounded portion that covers the reset wrench aperture with a stud similar to the stud 124 which cooperates with the arm 125 of the flash 126. This arm would be connected by a link similar to the link 116 to the slide 51 which it will be recalled is moved downwardly when either the sub-total lock 31 or the total lock 108 is unlocked. With this arrangement the flash 126 would be moved to ineffective position to allow the special transaction counters to be read in either total or sub-total printing operation.

The mechanism depicted in Fig. 13 serves to stop the reset shaft 121 in zero position after it has been turned one revolution to reset the wheels of the special counters. Secured on the shaft 121 is a disk 190 (see also Fig. 10) the hub of which has therein a clutch cut adapted to receive the tenons of the reset wrench 114 (Fig. 6).

The disk 190 has in the periphery thereof a V-shaped notch 191 which cooperates with the angular projection 192 of an arm 193 rotatably supported by a stud 194 secured in the special counter frame 122 and urged clockwise by a spring 195 into engagement with a stud 196 in the frame 122. Also loose on the stud 194 is an arm 197 with a bent-over ear 198 which is maintained in contact with the lower surface of the projection 192 of the arm 193 by a spring 199 which flexibly connects said arms 193 and 197. The arm 197 has in its upper end a semi-circular notch 200 which cooperates with a stud 201 fast in the disk 190 in a manner now to be described.

With the parts in the positions shown in Fig. 13, the wheels of the special counters are reset by inserting the reset wrench in the clutch cut of the disk 190 and revolving said disk and the shaft 121 in a clockwise direction. This causes the rounded edge of the V-shaped notch 191 to engage the angular projection 192 to rock the arm 193 counter clockwise against the tension of the spring 195. Due to the ear 198 the arm 197 rocks in unison with said arm 193 to move the notch 200 in the path of the stud 201 which by this time has moved beyond said arm 197. During continued rotation of the shaft 121 the periphery of the disk 190 in cooperation with the projection 192 maintains the arm 193 and the arm 197 in their counter clockwise positions until the stud 201 moves into the notch 200 sufficiently to prevent return movement clockwise of the arm 197. At this instant the circumferential surface of the disk 190 moves beyond the projection 192 freeing the arm 193 to the action of the spring 195 which returns it clockwise to its normal position. This indicates that the wheels of the special counter have been returned to zero and further movement of the shaft 121 in a clockwise direction is impossible due to the arm 197. Before another resetting movement of the shaft 121 can be made it is necessary to back up said shaft and the disk 190 in order to disengage the stud 201 from the notch 200. The spring 199 then returns the arm 197 to normal position as here shown in full line. Backing movement of the shaft 121 and the disk 190 is limited by means of the projection 192 which in cooperation with the notch 191 prevents further reverse movement of the disk 190.

The mechanism for actuating the special transaction counters and the special operation counter is shown in Figs. 7, 8, and 10, and will now be described. The units wheel of each of the transaction counters 120 and the operation counter 119 carries a ratchet 202 the teeth of which are engaged by a spring-urged feed pawl 203 supported by a yoke 204 straddling the wheels of each of said counters and pivotally supported by the shaft 121. The yoke 204 (Fig. 7) has pivoted thereto the forward end of a toggle link 205 the rearward end of which is pivoted at 206 to another toggle link 207, with a stud 208, which extends through a horizontal slot in a support plate 209 fixedly supported by the reset shaft 121 and a rod 210. Loosely connected to the pivot point 206 is the lower end of a link 211 the upper end of which is loose on a rod 212 the lefthand end of which is supported by an arm of a bell crank 213 pivoted at 214 to the plate 123 (see also Fig. 10), and the righthand end is supported by an arm 215 pivoted to the plate 122 in a similar manner to the bell crank 213. The upwardly extending arm of the bell crank 213 is connected by a link 216 to the machine operating mechanism which oscillates

said bell crank and the rod 212 first clockwise to the position shown in Fig. 7, and then back to normal position as shown in Fig. 8.

Journaled in the plates 122 and 123 (Figs. 7 and 10) is a shaft 217 having secured thereto a plurality of segments 218 located in uniform radial relation to each other, there being one segment for each of the special counters 120. The peripheries of the segments 218 cooperate with the studs 208 to select the different special transaction counters for actuation in a manner presently to be described. Secured on the shaft 217 is a pinion 219 connected by an intermediate gear 220 to a segment 221 fulcrumed at 222. The segment 221 is differentially positioned during the first part of machine operation by means of a settable transaction lever, or in some cases by means of a row of transaction keys. This positioning of the segment 221 is transmitted to the shaft 217 and locates the proper segment 218 opposite the stud 208. Immediately after the shaft 217 has been thus positioned the bell crank 213 receives its initial clockwise movement, which by means of the link 211 expands the toggle links 205 and 207 and due to the fact that rearward movement of the stud 208 is blocked, the yoke 204 is rocked clockwise against the tension of a spring 223 to cause the units wheel of that particular special counter to be advanced one increment of movement.

It is obvious that when rearward movement of the stud 208 (Figs. 7 and 8) is not blocked by one of the segments 218 said stud reciprocates idly in the slot in the plate 209, the spring 223 being strong enough to retain the yoke 204 in home position against a bent-over ear 224 of the plate 209.

As it is necessary for the special operation counter 119 (Fig. 10) to operate every machine operation, this counter is supplied with a disk 225 loose on the shaft 217 which in cooperation with the stud 208 causes one to be added to the special operation counter each machine operation. This, together with the fact that the special operation counter 119 has four wheels instead of three, is the only material difference between said counter and the special transaction counters 120.

While the form of mechanism herein shown and described is admirably adapted to fulfill the object primarily stated, it is to be understood that it is not intended to confine the invention to the one form or embodiment herein disclosed, for it is susceptible of embodiment in various forms, all coming within the scope of the claims which follow.

I claim:

1. In a machine of the class described adapted to print totals directly from the wheels of the totalizer, the combination of means to reset the totalizer; insertable means to operate the resetting means; means to lock the insertable means against removal upon insertion; and means supporting the locking means and adapted to retain the resetting means in home position, said supporting means adapted to be operated by insertion of the insertable means to free the resetting means and to move the locking means to effective position.

2. In a machine of the class described adapted to print sub-totals and totals directly from the wheels of the totalizer, the combination of means to print symbols characteristic of the sub-total and the total-printing operations; means to reset the totalizer; insertable means to operate the

resetting means; means to lock the insertable means against removal upon insertion; and an element to retain the resetting means in normal position and connected with said symbol printing means and said locking means, said element adapted to be moved by insertion of the insertable means to free the resetting means, to position the symbol printing means, and to move the locking means to effective position.

3. In a machine of the class described adapted to print sub-totals and totals directly from the wheels of the totalizer, the combination of means to print symbols characteristic of the sub-total and the total printing operations; means to reset the totalizer; insertable means to operate the resetting means; means to lock the insertable means against removal until a complete resetting movement thereof is performed; a step-by-step counting device to register the number of times the insertable means is inserted; and an element to retain the resetting means in normal position and connected with said symbol printing means and said locking means, said element adapted to be moved by insertion of the insertable means to free the resetting means, to position the symbol printing means, to move the locking means to effective position, and to cause the counting device to be advanced one unit.

4. In a machine of the class described having a totalizer, the combination of a reset mechanism for the totalizer; an element adapted to be inserted in an aperture in the machine to operate the reset mechanism; means effective when the element is removed to lock the reset mechanism in home position; means to obstruct movement of the reset mechanism after one operation thereof has been performed; means rendered effective by the obstructing means to prevent reinserting the element in the aperture; and resilient means effective upon machine operation to return the obstructing means to normal position, in which position reverse movement of the reset mechanism is blocked, and the preventing means is rendered ineffective.

5. In a machine of the class described adapted to print totals directly from the wheels of the totalizer, the combination of means to impress record material against the totalizer wheels; means to reset the totalizer wheels to zero; insertable means to operate the resetting means; means normally locking the impression means against operation; means to prevent resetting movement of the insertable means until the impression means has received its initial movement to print a total; and means whereby insertion of the insertable means moves the impression locking means to ineffective position to permit initial movement thereof, which in turn renders the preventing means ineffective.

6. In a machine of the class described adapted to print totals directly from the wheels of the totalizer, the combination of means to impress record material against the totalizer wheels; means to operate the impression means; means to reset the totalizer wheels to zero; insertable means to operate the resetting means; means normally locking the impression operating means against printing movement; means to prevent resetting movement of the insertable means until the impression operating means has received initial movement to print a total; a member co-operating with the locking means for the impression operating means; and means operated by insertion of the insertable means to actuate

the member to move the locking means to ineffective position.

7. In a machine of the class described adapted to print totals directly from the wheels of the totalizer, the combination of means to impress record material against the totalizer wheels; means to operate the impression means; means to reset the totalizer to zero; insertable means to operate the resetting means; a member with 5 two positions the first of which locks the insertable means against resetting movement until an impression is made, and the second of which frees the insertable means and locks the impression operating means in moved position; re- 10 silent means to move the member to its second position upon initial movement of the impression operating means; means on the impression operating means to retain the member in first position; means to block movement of the impression 15 operating means; and means operated by insertion of the insertable means to render the blocking means ineffective.

8. In a machine of the class described adapted to print totals directly from the wheels of the totalizer, the combination of means to impress record material against the totalizer wheels; means to operate the impression means; means to reset the totalizer wheels; insertable means to operate the resetting means; and an interlocking 20 device intermediate the impression operating means and the insertable means to render the latter inoperative until the impression operating means receives printing movement, which movement causes the interlocking device to free the 25 insertable means and lock the impression operating means in moved position.

9. In a machine of the class described adapted to print totals directly from the wheels of the totalizers, the combination of means to impress record material against the totalizer wheels; means to operate the impression means; means to reset the totalizer wheels; insertable means to operate the resetting means; an element to lock the impression operating means against 30 printing movement; a member to lock the insertable means inoperative until the impression operating means receives printing movement; and means operated by insertion of the insertable means to move the element to ineffective position.

10. In a machine of the class described adapted to print totals directly from the wheels of the totalizer, the combination of means to impress record material against the totalizer wheels; means to operate the impression means; means to reset the totalizer wheels; insertable means to operate the resetting means; an element normally locking the impression operating means against printing movement; a spring-urged 35 member held in normal position by the impression operating means to block resetting movement of the insertable means, said member upon printing movement of the impression operating means adapted to free the insertable means and block return movement of the impression operating means; a resilient element associated with the member and normally locking the impression operating means against printing movement; and means operated by insertion of the insertable means 40 to move the element to ineffective position, return movement of said element upon removal of the insertable means adapted to restore the member to normal position.

11. In a machine of the class described adapted to print totals directly from the wheels of the 45

totalizer, the combination of insertable means to reset the totalizer; means to impress record material against the wheels of the totalizer; means to lock the impression means inoperative; a shiftable inking device for the impression means; and means actuated by insertion of the insertable means to shift the inking device and simultaneously render the locking means ineffective. 5

12. In a machine of the class described adapted to print totals directly from the totalizer wheels, the combination of means to impress record material against the totalizer wheels; means to operate the impression means; means normally effective to lock the impression operating means against printing movement; insertable means to 10 reset the totalizer; a shiftable device supporting a bi-chrome inking ribbon for the impression means; a member actuated by insertion of the insertable means; and means intermediate the member and the shiftable device to shift said 15 device and simultaneously render the locking means ineffective.

13. In a machine of the class described adapted to print totals directly from the totalizer wheels, the combination of means to impress record material against the totalizer wheels; means to operate the impression means; means normally effective to lock the impression operating means against printing movement; insertable means to 20 reset the totalizer to zero; a shiftable device supporting a bi-chrome inking ribbon for the impression means; a member actuated by insertion of the insertable means; an element operated by the member; and means whereby the element shifts the device and simultaneously renders the 25 locking means for the impression operating means ineffective. 30

14. In a machine of the class described adapted to print totals directly from the totalizer wheels, the combination of means to impress record material against the totalizer wheels; a closure giving access to the impression means; a lock on the closure; insertable means to reset the totalizer wheels; an aperture to receive the insertable means; machine operating means; means to lock the machine operating means; means normally obstructing the aperture, said obstructing means also adapted to control the closure locking means and the locking means for the machine operating means; and a main lock 50 to control the obstructing means.

15. In a machine of the class described adapted to print totals directly from the totalizer wheels, the combination of means to impress record material against the totalizer wheels; a closure giving access to the impression means; a lock on the closure; a plurality of counting devices; insertable means to reset the totalizer wheels and the counting devices; apertures opposite the totalizer wheels and the counting devices adapted to receive the insertable means; a flash to control visibility of the counting devices; a shutter for the aperture for the counting devices, said shutter adapted to operate the flash; machine operating means; means to lock the machine operating means; means normally obstructing the aperture for the totalizer wheels, said obstructing means also adapted to control the closure locking means, the locking means for the machine operating means, and the shutter for the aperture for the counting devices; and a main lock 60 to control the obstructing means. 55

16. In a machine of the class described adapted to print totals directly from totalizer wheels, the combination of means to impress record material 70 75

against the totalizer wheels, means to actuate the impression means, a record material controlled latch for latching said actuating means whenever no record material is in printing position, means to reset the totalizer wheels, insertable means to operate the resetting means, means normally locking said actuating means against operation, means to prevent resetting movement of the insertable means until the actuating means has received an initial movement, and means controlled by the insertable means to move the actuator locking means to ineffective position, said latch and actuator locking means compelling the presence of record material at the printing point and the insertion of the insertable means in order that the actuating means may be unlocked so that it may be operated to actuate the impression means and unlock the reset preventing means.

17. In a machine of the class described having means to print totals directly from totalizer wheels, the combination of means to actuate the total printing means, a closure giving access to the printer actuating means, a lock for the closure, a shaft operable to reset the totalizer wheels, means to engage the end of the shaft to operate it whereby the wheels may be reset, machine operating means, locking means for the machine operating means, means normally shielding the end of the reset shaft to prevent the shaft from

being engageable by its operating means, said shielding means also controlling the closure locking means and the locking means for the machine operating means, and a main lock to control the effectiveness of the shielding means. 5

18. In a machine of the class described having means to print totals from totalizer wheels, the combination of means to actuate the total printing means, a closure giving access to the printer actuating means, a lock for the closure, 10 plurality of counting devices, a reset shaft for the totalizer, a reset shaft for the counters, means selectively engageable with the ends of the shafts to actuate them whereby the counting devices or totalizer wheels controlled thereby may be reset, a flash to control the visibility of the counting devices, a first shield for covering the end of reset shaft for the counting devices, said shield being connected to operate the flash, machine operating means, locking means for the machine 20 operating means, a second shield for covering the end of the totalizer wheel reset shaft, said first and second shields being adapted to prevent engagement of the shafts and their actuating means, connections from the second shield to 25 control the closure locking means, the locking means for the machine operating means and the first shield, and a main lock for controlling the effectiveness of the second shield.

RICHARD FELLENBERG. 30
